Des. 204,641
Patented May 3, 1966

204,641

WATERPROOF CONTAINER FOR ACCESSORIES

Owsley H. Brigham, 6201 N. Delaware St.,
Indianapolis, Ind.

Filed Jan. 11, 1965, Ser. No. 83,387

Term of patent 14 years

(Cl. D58—17)

Fig. 1.

Fig. 2.

Fig. 3.

Fig. 4.

Fig. 5.

FIG. 1 is a front elevation of a waterproof container for accessories, showing my new design.

FIG. 2 is a side elevation of said container.

FIG. 3 is a bottom plan view of said container.

FIG. 4 is a top plan view of said container.

FIG. 5 is a rear elevation of said container.
The undisclosed side of said container is substantially the same in appearance as the side shown.

I claim:

The ornamental design for a waterproof container for accessories, as shown and described.
